TAIL GATE ELEVATOR

Wilfred M. Woodward, New Brunswick, N. J.

Application October 13, 1948, Serial No. 54,299

6 Claims. (Cl. 214—75)

1

My invention relates to a screw-propelled tail-gate elevator and more particularly to an improvement in the construction and relationship of parts in such a device.

This application replaces and relates back for subject matter to my application Serial No. 645,282 filed February 4, 1946 and now abandoned.

It is an object of the invention to provide a screw-propelled tail-gate elevator which has no part projecting to the ground when the gate is elevated to its position at the truck platform.

It is another object of the invention to provide a screw-propelled tail-gate elevator in which the screw drive is located adjacent the truck platform and in which the load is not transmitted through the drive mechanism.

Another object of the invention is to provide a screw-propelled tail-gate elevator which may be of relatively light weight and yet handle heavy loads without binding or flexure of the screws.

These and other objects of the invention and the various features and details of the construction and operation thereof are hereinafter fully set forth and described with reference to the accompanying drawings, in which:

Fig. 1 is a view in perspective of the rear end of a truck embodying the present invention and showing the tail-gate in the elevated and closed position;

Fig. 2 is an enlarged view similar to Fig. 1 showing the tail-gate in the elevated open position, the lowered position thereof being shown in dotted lines;

Fig. 3 is a perspective view of a tail-gate made according to the present invention;

Fig. 4 is an enlarged sectional view taken on line 4—4, Fig. 3;

Fig. 5 is an enlarged sectional view taken on line 5—5, Fig. 4;

Fig. 6 is an enlarged fragmentary sectional view through the drive mechanism for lowering and elevating the tail-gate; and

Fig. 7 is a sectional view taken on line 7—7, Fig. 6.

Referring now more particularly to the drawings, reference numeral 1 designates a tail-gate which is hinged as indicated at 2 to a cross-member 3. In accordance with the present invention, the tail-gate 1 is mounted for vertical movement between the lowered and elevated positions shown in Fig. 2 of the drawings. To this end, therefore, the cross-member 3 is rigidly connected at each end to a vertical column 4 adjacent the lower end thereof. The columns 4 are hollow, and preferably of square or rectangu-

2

lar cross-section shape as indicated, and are mounted to slide telescopically within fixedly mounted outer columns or posts 5 of a correspondingly larger cross-sectional size and shape.

5 By making the telescoping pairs of columns 4 and posts 5 of square or rectangular cross-sectional shape as shown and described, greater rigidity and strength are imparted to the structure with the result that the load capacity of the tail-gate is substantially increased. In addition, such square or rectangular structural shapes are usually employed for the frame posts of the bodies of vehicles and hence the outer posts 5 may constitute the customary rear frame posts of the body 6 of a truck or vehicle 7 as shown in Figs. 1 and 2. Thus, the tail-gate of the present invention may be manufactured in such manner that the columns 4 may slide telescopically within the rear frame posts of existing truck bodies or the tail-gate may be incorporated readily into a truck or vehicle body in the course of its manufacture without material deviation from its originally designed construction.

The outer face of each of the fixed columns 5 or posts 5 is provided with a longitudinal slot 8 which extends upwardly therein a predetermined distance from the bottom edge of the column, and provides an opening or track for the passage of an outwardly projecting lug 9 which is carried by each column 4. Pivoted braces 10 may be connected between opposite ends of the tail-gate 1 and the lugs 9 to support the gate in horizontal position and to permit it to be swung about the hinge 2 to a vertical position when not in use, for example, as shown in Figs. 1 and 2 of the drawings.

The lower end of each of the columns 4 is provided with a cap or closure 11 which has a portion 12 of reduced size arranged to fit into the end of the column and providing a peripheral shoulder 13 upon which the lower end edges of the column are adapted to seat, for example, as shown in Fig. 4 of the drawings. The upper end of each of the columns 4 is provided with a similar cap or closure 14 which likewise has an inserted portion 15 of reduced size providing a peripheral shoulder 16 that is adapted to engage or seat upon the upper end edges of the column.

Extending longitudinally within each of the columns 4 is a threaded bar 17 which has its opposite ends secured in the end caps 11 and 14, respectively, in a manner to prevent rotation of the bars 17 with respect to the columns. Thus, the lower and upper ends of the bars 17 may be provided with reduced portions 18 of square or

rectangular cross-sectional shape which engage slidably within elongated rectangular slots 19 in the lower and upper caps or closures 11 and 14, respectively. The bars 17 are further provided with projecting threaded end portions 20 that receive nuts or the like 21 as more clearly shown in Fig. 5 of the drawings, the arrangement being such that when the nuts 21 are tightened upon the ends 20 of the bars 17, the nuts do not bind against the caps 11 and 14 to prevent movement of the ends of the bars 17 within the slots 19. By this construction and arrangement it will be observed that the bars 17 are effectively anchored against rotation and that they serve also as tie-rods to retain the caps 11 and 14 in and firmly against the opposite ends of the columns 4.

It is to be noted that the elongated slots 19 provided in the caps or closures 11 and 14 at the lower and upper ends of the columns 4 have their long axes extending in the fore and aft direction with respect to the truck or vehicle 7 in which the device is installed and, as previously stated, the reduced square or rectangular portions 18 of the bars 17 slidably engage within the slots 19 so that the ends of said bars may move in a fore and aft direction within the limits of the slots 19. The ends of the bars 17 are thus provided with a floating mounting which permits movement of the columns 4 and end closures 11 and 14 relative to the bars 17, thus preventing bending of the bars 17 and consequent binding thereof in the threaded sleeve 28. This structure is advantageous for the easy operation of very light apparatus when excessive loads are imposed on the tail gate 1. A heavy load tends to flex the columns 4, and if these columns are light, and if a rigid connection existed between these columns and the bars 17, the latter would also tend to flex and cause the undesired binding action referred to above in which case it would be very difficult, if not impossible, to properly operate the mechanism.

Fixedly secured to the inner face of each outer column 5 at the lower end thereof and beneath the floor 22 of the vehicle body 6, is a bracket 23 having arm portions 24 that extend through suitable openings 25 in the columns 5 and inwardly of the telescoping columns 4 through elongated slots 26 which extend longitudinally in each column 4 from a point adjacent the lower end thereof to a predetermined point adjacent the upper end of the column. The inwardly extending arm portions 24 of the brackets 23 terminate in collar portions 27 which surround the threaded bars 17 in spaced relation axially thereof as shown in Fig. 6 of the drawings.

Threaded on each bar 17 intermediate the collar portions 27 is a sleeve 28 which has its opposite ends journaled in said collar portions 27 by means of bearings 29, and secured upon or formed integral with each sleeve 28 intermediate its ends is a spiral gear 30. Each of the spiral gears 30 meshes with a similar spiral gear 31 that is fixed upon a shaft section 32 which is journaled in spaced aligned sleeve portions 33 of the brackets 23, and thrust bearings 34 are interposed between said sleeve portions 33 at opposite sides of the gears 31. One of the shaft sections 32 and its associated spiral gear 31 is adapted to be rotationally driven by means of a hand crank 35, and driving connection from said one shaft 32 to the other may be established through an intermediate shaft 36 connected therebetween, for example, by means of universal joint connections 37, as shown in the drawings.

From the foregoing description it will be observed that with the tail-gate 1 in the position shown in Fig. 2 of the drawings, actuation of the crank 35 in a clockwise direction with respect to the drawings will cause the gears 31 to rotationally drive the gears 30 and sleeves 28 in counterclockwise direction with respect to Fig. 7 thereby causing the threaded bars 17 to feed downwardly carrying with them the inner columns 4, cross-member 3 and tail-gate 1 to the dotted line position shown in Fig. 2. On the other hand, actuation of the crank 35 in clockwise direction operates to drive the sleeves 28 in the reverse direction of rotation thereby causing the bars 17 to feed upwardly through the sleeves and, of course, causing the columns 4 to telescope within the columns 5 thereby elevating or raising the tail-gate 1 from the dotted line position of Fig. 2 to the solid line position therein.

From the foregoing description it will be observed that the present invention provides a tail gate having novel and improved mechanism for lowering and raising the tail gate and embodying features of construction operable to prevent binding of the lift mechanism as a result of stresses and strains imposed thereon by bending moments produced when loads of great weight are raised or lowered upon the tail gate. The invention also provides a tail gate construction of the character set forth which may be readily and easily incorporated in and as a part of the body structure of a vehicle in the course of manufacture thereof or subsequently. The invention furthermore provides a device of the character described which is of relatively simplified and economical construction and which may be readily manufactured, assembled and installed.

While a particular embodiment of the present invention has been illustrated and described herein, it is not intended to limit the invention to such disclosures and modifications may be made therein and thereto within the scope of the claims.

I claim:

1. The combination with a vehicle body of a tail-gate elevator comprising a pair of fixed vertical posts, a pair of columns slidably journaled in said posts for movement up and down, a tail-gate hinged to the lower ends of said columns for movement between vertical and horizontal positions, a pair of fixed bracket members, an internally threaded sleeve journaled in each of said bracket members in a manner to take vertical thrust, driving mechanism connected to rotate said sleeves, a pair of screw bars each secured at its ends to the top and bottom of one of said columns and threaded in one of said sleeves, said fixed brackets and the lower ends of said fixed posts being located adjacent the floor of said vehicle body.
2. The combination as set forth in claim 1 in which said posts are hollow, and said columns are telescoped inside said posts, the columns being slotted to pass said bracket members.
3. The combination as set forth in claim 1 in which said posts are hollow, and said columns are telescoped in said posts, the columns being slotted to pass said bracket members, and said tail-gate is provided with folding braces to strengthen the tail-gate in horizontal position, said posts being slotted to pass said braces.
4. The combination as set forth in claim 1 in which the ends of said screw bars are secured to said columns in a manner to permit limited horizontal movement of the bar within the column

whereby a load tending to flex a column does not flex its screw bar.

5. A tail-gate elevator comprising a pair of fixed vertical posts, columns slidably journaled in said posts for vertical movement, a cross member secured between the lower ends of said columns, a tail-gate hinged to said cross member for pivotal movement between vertical and horizontal positions, collapsible braces pivotally connected between said columns and the outer ends of said tail-gate to support the same in horizontal position, vertical slots in said posts for reception of a portion of said braces, bracket members fixed on said posts and projecting inwardly of said posts and said columns, internally threaded sleeves journaled on said members, a gear on each of said sleeves, driving gears rotatably mounted in said brackets and meshing with said first named gears, top and bottom closures on said columns, said closures each having a slot therein extending in a direction normal to the hinge axis of said tail-gate, screw bars threaded in said sleeves, the end portion of said bars being slidably received in said slots whereby upon flexure of said columns under the action of a load on said tail gate bending of said bars and consequent binding thereof in said sleeves is prevented, said bars being fixed in said closures against rotation and longitudinal movement relative thereto whereby upon rotation of said driving gears said sleeves will be rotated to move said bars and said tail-gate up or down.

6. A tail-gate elevator comprising a pair of fixed vertical posts, columns telescopically received within said posts for vertical movement

relative thereto, a tail-gate hingedly connected to said columns for pivotal movement between vertical and horizontal positions, bracket means fixed on said posts, internally threaded sleeves 5 rotatably mounted on said bracket means, driving means for said sleeves, top and bottom closures on said columns, said closures each having a slot therein extending in a direction normal to the hinge axis of said tail-gate, threaded bars 10 extending longitudinally within said columns, and threadedly engaging said sleeves, the end portions of said bars being slidably received in said slots, said bars being fixed in said closures against rotation and longitudinal movement relative thereto, whereby upon actuation of said driving means said sleeves will be rotated to move said bars and said tail-gate up or down and whereby any flexure of said columns under the action of a load on said tail-gate will not be 15 transmitted to said bars thus preventing binding of said bars in said sleeves.
